ASSIGNORS TO GLENS FALLS IMPROVED TROLLEY FORK COMPANY, OF
GLENS FALLS, NEW YORK.

TROLLEY-HARP.

No. 846,205.

Specification of Letters Patent.

Patented March 5, 1907.

Application filed February 28, 1906. Serial No. 303,408.

To all whom it may concern:

Be it known that we, CHARLES HIBBARD and WARREN HIBBARD, citizens of the United States, and residents of Sandy Hill, in the county of Washington and State of New York, have invented a new and Improved Trolley-Harp, of which the following is a full, clear, and exact description.

Our invention relates to trolley-harps, our more particular purpose being to provide means for mounting the trolley-wheel upon the harp and for removing the same therefrom, and also for maintaining the wheel-mountings firmly in position while the wheel is in place.

Reference is to be had to the accompanying drawings forming a part of this specification, in which similar characters of reference indicate corresponding parts in all the figures.

Figure 1 is a vertical section through the trolley-harp, showing the wheel mounted in position, and also showing the mechanism for enabling the wheel to be removed and replaced. Fig. 2 is a vertical section upon the line 2 2 of Fig. 1 looking in the direction of the arrow and showing one of the disks used for holding the stub-shaft which carries the trolley-wheel. Fig. 3 is a view somewhat similar to Fig. 2, but showing the disk as occupying a different position to facilitate the removal of the stub-shaft. Fig. 4 is an enlarged horizontal section upon the line 4 4 of Fig. 1 looking in the direction of the arrow and showing the locking mechanism for holding the adjusting nut in any desired predetermined position. Fig. 5 is a perspective view of the stub-shaft for carrying the trolley-wheel. Fig. 6 is a perspective view of one of the sheet-metal guards used for guiding the stub-shaft into and out of its normal position and also for protecting certain movable parts. Fig. 7 is a perspective view of a spanner-wrench for turning the movable nut 37 by means of the adjusting-wheel 38; and Fig. 8 is a reduced fragmentary elevation, somewhat similar to Figs. 2 and 3, but showing the sheet-metal guards 21 as mounted in position and partially covering one of the disks 15.

The trolley-stem is shown at 6, and is provided with a reduced portion 7, upon which fits a fork 8, the latter being secured in posi-

tion by means of a pin 9. Extending upwardly from the reduced portion 7 and integral therewith is a screw 10. The fork 8 comprises two standards 11 integral therewith and spaced apart, as will be understood from Fig. 1. Each standard 11 is provided with an aperture approximately circular in general outline, this aperture merging into a substantially V-shaped aperture 13, the wall of which serves as a bearing portion. A slot 14 also merges into the aperture 12 and extends to the edge of the standard.

Upon each standard 11 is a disk 15, provided with a flattened portion 15^a and with an aperture 15^b. Adjacent to each disk 15 is a slot 16, and extending from each disk 15 through the adjacent slot 16 is a revolute stem 17, provided with a head 18. The arrangement is such that each disk 15 has a vertical play, for the reason that its stem 17 can move slightly in its slot 16, as will be understood from Fig. 1. Each standard 11 is provided immediately below its slot 16 with an arcuate slot 19, which is concentric to the slot 16. Mounted upon the disks 15 and projecting outwardly through the arcuate slots 19 are two studs 20. By means of these studs the disks can be turned or rocked within certain limits, as will be understood from Figs. 1, 2, and 3. Two guards 21, of sheet metal, are mounted adjacent to the disks 15, so as to partially cover the same. Each guard 21 is provided with screw-holes 22, through which pass screws 23 for holding the guard in position. Each guard 21 is further provided with a slot 24 of the shape indicated in Fig. 6. This slot is bounded by fingers 25 26 integral with the guard 21 and adapted to be bent outwardly, as indicated in Figs. 6 and 8. These sheet-metal guards 21 are mounted directly upon the standards 11 and retain sliding lugs 27 and other movable parts, the lugs 27 being disposed in passage-ways 28, having the form of vertical slots, as indicated in Fig. 3. By having the fingers 25 26 bent outwardly the washers 22 are unable to slip behind them while the wheel and stub-shaft are being inserted. A stub-shaft 29, hereinafter described, is provided with prismatical ends 30 integral therewith and is adapted to be inserted into the fork, so that the prismatical ends 30 enter the bearing-apertures 13. For this purpose the disks 15

are rotated slightly, as above described. In order to admit the stub-shaft 29, the disks 15 are turned by means of the studs 20 into the position indicated in Fig. 2. The stub-shaft 29 is then inserted, so that the prismoidal ends 30 enter the apertures 15^b. The disks are then rotated by means of the studs 20, so as to bring the prismoidal ends 30 into the position indicated in Fig. 3. The stub-shaft 29 is now raised by hand, so that the prismoidal ends 30 fit neatly into the bearing-apertures 13, and the disks 15 are turned by means of the studs 20, so that the facets 15^a of the disks engage the prismoidal ends 30, as indicated in Fig. 2. The disks are now locked in position by means of the movable lugs 27. For this purpose each lug 27 is provided at its upper end with an arcuate surface 31, conforming substantially to the shape of the disks 15 immediately over it, so that when the sliding lugs 27 are raised, as indicated in Fig. 2, they press the disks 15 against the prismoidal ends 30 of the stub-shaft 29 and hold the same rigidly in its normal position. Washers 32 encircle the stub-shaft 29 and center the trolley-wheel which is shown at 33. This wheel is provided with axial sleeves 33^a 34, the latter turning directly upon the stub-shaft, as will be understood from Fig. 1. Mounted within the bottom of the fork is a movable plate 35, provided with a central aperture 36, which encircles the screw 10. This plate 35 engages directly the lower ends of the sliding lugs 27 and is adapted to raise the same if the plate 35 is raised. Revolvably mounted upon the screw 10 is a nut 37, provided externally with an adjusting-wheel 38, rigid relatively thereto and serving to operate the same. A locking-plate 39 is provided with an upturned flange 40, which prevents displacement of the movable plate 35, as will be understood from Fig. 1. This flange 40 extends into a slot 41, so as to be flush with the outer adjacent edge of the standard 11. The opposite end of the locking-plate 39 is provided with a tongue 42, which extends into a slot 43, and thus serves as a guide for maintaining the plate 39 in a given plane, or, in other words, to prevent lateral displacement of the plate 39, as will be understood from Fig. 4. A spring 44 is mounted rigidly upon one of the standards 11 and engages a lug 45, projecting downwardly from the under side of the locking-plate 39. This lug 45 engages the adjusting-wheel 38, as indicated by dotted lines in Fig. 4, and normally prevents this adjusting-wheel from being turned. A spanner-wrench 46 (see Fig. 7) is provided with a fork 47 for encircling the lug 27 and is further provided with a lug 48 for engaging the outer edge of the adjusting-wheel 38. This is an ordinary spanner-wrench. It is used by placing it in such position that the fork 47 straddles the nut 37, the lug 48 being thus brought into engagement with the adjusting-

wheel 38. The flange 40 being now pressed by the operator's thumb the lug 45 disengages the adjusting-wheel 38, and the spanner-wrench 46, having been placed in position, as just described, the adjusting-wheel 38, carrying with it the revoluble nut 37, is turned. By this means the movable plate 35 is raised or lowered, and consequently the sliding lugs 27 are likewise raised and lowered. The guards 21, in addition to the purposes above stated, serve as contact-springs. They insure good electrical contact between the trolley-wheel and the body of the harp.

The operation of our system is as follows: Assuming that the stub-shaft 29 is in its normal position, as indicated in Figs. 1 and 2, the operator in order to remove it presses the flange 40 and turns the adjusting-wheel 38 by means of the spanner-wrench 46, thus lowering the sliding lugs 27. Then by means of the studs 20 he rotates the disks 15 into the position indicated in Fig. 3 and then turns these disks in a direction which, according to Fig. 3, would be clockwise, so that the stub-shaft may be removed through the slot 14. In order to replace the stub-shaft, (provided with the wheel, if desired,) the reverse operation is carried out, the stub-shaft being carried in through the slot 14 and ultimately lodged in such position that the prismoidal ends 30 fit into the positions indicated in Figs. 1 and 2. In this case the last step in turning the adjusting-wheel 38 to its final position is that the operator removes his thumb from the flange 40 and allows the lug 45 to lock the adjusting-wheel 38 in position, as indicated by dotted lines in Fig. 4.

Having thus described our invention, we claim as new and desire to secure by Letters Patent—

1. The combination of a member provided with standards spaced apart and provided with apertures and with bearing portions merging into said apertures, a stub-shaft provided with ends adapted to fit said bearing portions, disks mounted within said apertures and provided with portions for engaging said stub-shaft, being adapted to move slightly in a direction crossing the general plane of rotation of said disks; means for moving said disks by hand, and mechanism for locking said disks rigidly against said stub-shaft.

2. The combination of a fork provided with slots and with bearing portions, revolvable disks connected with said fork and provided with apertures adapted to register with said slots and also adapted to register with said bearing portions, means controllable at will for turning said disks, said disks being adapted to travel laterally in a direction crossing the plane of revolution of said disks, lugs provided with portions for engaging said disks, and mechanism controllable by hand for forcing said lugs toward said disks.

3. The combination of a fork, a stub-shaft mounted therein and adapted to support a trolley-wheel, revoluble disks coacting with said fork for locking said stub-shaft rigidly in relation thereto, sliding lugs for engaging said revoluble disks, a movable plate for actuating said sliding lugs, and screw mechanism for moving said movable plate.
4. The combination of a fork, a stub-shaft mounted therein and adapted to support a trolley-wheel, revoluble disks coacting with said fork for locking said stub-shaft rigidly in relation thereto, sliding lugs for engaging said revoluble disks, a movable plate for actuating said sliding lugs, screw mechanism for moving said movable plate, and means for locking said screw mechanism in a predetermined position.
5. The combination of a fork, a stub-shaft mounted therein, revoluble members for placing said stub-shaft in position relatively to said fork and for displacing the same, means for forcing said revoluble members in a direction lateral to the general direction of rotation thereof so as to hold said stub-shaft in position and to release the same from said position, and sheet-metal plates mounted upon said fork and partially covering said revoluble members and said mechanism for actuating the same.
6. The combination of a fork, a member mounted thereupon and adapted to support a trolley-wheel, revoluble disks mounted upon said fork and adapted to permit the insertion and removal of said member, lugs engaging said disks for clamping the same in predetermined positions, a movable plate engaging said lugs for the purpose of forcing the same in a predetermined direction, and means controllable at will for actuating said movable plate.
7. The combination of a fork provided with a bearing portion, and an aperture merging therewith and provided with a slot, a sheet-metal guard connected with said fork and provided with a slot registering with said aperture, said bearing portion and said slot of said fork, a stub-shaft provided with ends for engaging said bearing portions, said ends being adapted to follow said slot and said aperture of said fork, and means for clamping the ends of said stub-shaft rigidly against said bearing portions.
8. A trolley-harp, comprising a fork provided with slots and with bearing portions disposed adjacent to said slots, revoluble disks mounted upon said fork and movable relatively thereto in a direction crossing the general plane of revolution of said disks, said revoluble disks being provided with apertures adapted to register with said slots, a pin provided with end portions for fitting into said slots of said fork, and also into said apertures of said disks, said end portions of said pin being of proper conformity to fit against said bearing portions of said fork, and means for locking said disks.
9. The combination of a fork provided with angular bearing portions and with apertures leading thereto, a stub-shaft provided with angular ends adapted to engage said bearing portions and to follow said apertures leading thereto, and means for positively locking said stub-shaft relatively to said fork.
10. The combination of a fork, a stub-shaft mounted thereupon and adapted to support a trolley-wheel, pressure mechanism connected with said fork and detachably engaging said stub-shaft for the purpose of holding the same in position to said fork, and means controllable at will for varying the degree of pressure exerted by said pressure mechanism against said stub-shaft.
11. The combination of a fork provided with bearing portions, a shaft mounted upon said fork and provided with portions engaging said bearing portions, said shaft being adapted to support a trolley-wheel, a movable member connected with said fork and temporarily engaging said shaft for the purpose of holding the same in position, and means controllable at will for adjusting said movable member relatively to said shaft.
12. The combination of a fork provided with bearing portions and with apertures leading thereto, a member provided with surfaces for engaging said bearing portions, said surfaces being adapted to follow said apertures, a trolley-wheel mounted upon said member, and mechanism including an adjustable screw for retaining said member temporarily in a predetermined position relatively to said fork.
